CHAIR

Morton Pearlstine, Cynwyd, Pa., assignor to The Bunting Company, Inc., Philadelphia, Pa., a corporation of Pennsylvania

Application January 18, 1956, Serial No. 39,832

Term of patent 14 years

(Cl. D15—11)

Figure 1 is a side elevational view of a chair showing my new design, the seat and back thereof being shown swung into position for more or less upright occupancy;

Figure 2 is a front perspective view of the chair;

Figure 3 is a rear elevational view of the chair; and

Figure 4 is a side elevational view similar to Figure 1 but showing the seat and back of the chair swung into position for reclining occupancy thereof.

The dominant features of my design reside in the parts shown in solid lines.

I claim:

The ornamental design for a chair, as shown and described.
